Primary Examiner — Rebecca Tsehay(74) *Attorney, Agent, or Firm* — Woodard Emhardt Henry Reeves & Wagner(57) **CLAIM**

The ornamental design for the handheld vaping instrument as shown and described.

DESCRIPTION

FIG. 1 illustrates an isometric perspective view of a handheld vaping instrument showing my design;

FIG. 2 is a right perspective view thereof;

FIG. 3 is an enlarged top perspective view thereof;

FIG. 4 is a forward perspective view thereof;

FIG. 5 is an enlarged bottom perspective view thereof;

FIG. 6 is a left perspective view thereof; and,

FIG. 7 is a rear perspective view thereof.

The broken lines in the drawings depict portions of the handheld vaping instrument that form no part of the claimed design.
